[57] CLAIM

The ornamental design for a locomotive solid fuel gasifier unit, as shown and described.

DESCRIPTION

FIG. 1 is a perspective view of a locomotive solid fuel gasifier unit showing my new design;

FIG. 2 is an end view thereof, the opposite end being a mirror image;

FIG. 3 is a top plan view thereof;

FIG. 4 is a side elevational view thereof, the opposite side being a mirror image;

FIG. 5 is a perspective view of a locomotive solid fuel gasifier unit showing a second embodiment of my new design;

FIG. 6 is an end elevational view thereof, the opposite end being a mirror image;

FIG. 7 is a top plan view thereof; and,

FIG. 8 is a side elevational view thereof, the opposite side being a mirror image.

The broken lines shown in FIGS. 2, 4, 6 and 8 are for illustrative purposes only and form no part of the claimed design.

*FIG. 3**FIG. 4*FIG. 7

FIG. 8
